UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

ORNAMENTAL-STITCH SEWING-MACHINE.

1,334,650.

Specification of Letters Patent. Patented Mar. 23, 1920.

Application filed September 9, 1916. Serial No. 119,211.

To all whom it may concern:

Be it known that I, ALBERT H. DE VOE, a citizen of the United States, residing at Westfield, in the county of Union and State 5 of New Jersey, have invented certain new and useful Improvements in Ornamental-Stitch Sewing-Machines, of which the following is a specification, reference being had therein to the accompanying drawings.

- 10 This invention relates to improvements in ornamental stitch sewing machines and especially to machines having stitch-forming mechanism comprising one or more needles and complementary loop-taking means, and 15 thread-handling mechanism for the ornamental thread including one or more thread-looping implements or loopers mounted for universal movement transversely of the needle or needles and adapted to present a 20 thread or threads to the needle or needles in the formation of various ornamental seams differing in configuration.

The present construction is an improvement of the machine disclosed in the patent 25 to Griffiths, No. 767,688, of August 16, 1904, in which a single thread-looping implement is mounted on a carrier supported by the presser-bar and adapted to move in transverse directions, its respective movements 30 being produced by independent connections with two rotary cams mounted on two auxiliary shafts geared to the needle-actuating shaft.

In the present improvement the use of 35 cams is avoided and a single auxiliary shaft serves, through link-and-lever connections, to impart operative movements to one or more thread-looping implements mounted for universal movement transversely of the 40 needles, the object being to provide a high speed quiet running machine.

The invention has for another object to 45 provide mechanism for producing a composite seam of the character disclosed in my Patent No. 1,201,446, of October 17, 1916.

Another object of the invention is the 50 arrangement of a pair of thread-looping implements, one in front and one in rear of the needles, and the provision of means for moving said implements in unison laterally of the line of seam-formation and simultaneously toward or away from the plane of the needles.

Another object of the invention is the 55 provision of a simplified thread-controlling

mechanism for the ornamental thread or threads, acting to accurately measure and pay out thread to the looper or loopers for the purpose of controlling the configuration and preventing distortion of the loops previously laid by the looper or loopers about the needle or needles. Such thread-controlling mechanism is particularly desirable during the formation of ornamental seams when certain of the needle-threads are 60 omitted from the machine, as will herein-after more fully appear.

In the present construction the loopers are supported by a presser-bar, as in the Griffiths machine, and another object of the 70 invention is the provision of means for locking the main-shaft against rotation when the presser-bar is lifted and the prevention of upward movement of the presser-bar except when the loopers are in a predetermined position, to prevent possible damage 75 to the needles or loopers.

Further objects of the invention will appear from the following description and claims.

In the preferred embodiment of the invention, a machine is utilized which is adapted to make four parallel rows of single-chain stitches and comprises the usual flat bed-plate and overhanging bracket-arm 80 terminating in a head in which the needle and presser-bar are journaled. An auxiliary shaft extends crosswise of and is geared to the needle-driving shaft and carries two crank members which serve, re- 85 spectively, through link and lever connections to impart movements to a rocking frame and a bellcrank-lever fulcrumed in said rocking frame for movement therewith. The connections above mentioned include 90 a toggle device adapted to cause oscillations of the bellcrank-lever about its fulcrum at double the frequency of oscillation of said rocking frame.

Two loopers are supported respectively in 100 front and in rear of the needles by two looper-levers pivotally mounted on a carrier which is pivoted to a support carried by the presser-bar, thus adapting the loopers for universal movement transversely of the 105 needles. The bellcrank-lever above described is connected to impart its compound movements to said loopers, whereby each looper is caused to loop its thread about each of two adjacent needle paths alternately. 110

The thread controlling mechanism for the ornamental threads comprises a thread nipper and a single implement rigidly secured to the needle-bar and having a portion adapted to actuate the thread nipper and another portion to pull thread from the supply. An adjustable thread guide is provided to vary the effective action of the pull-off implement.

10 In the accompanying drawings, Figure 1 is a front elevation of the machine, partly in section. Fig. 1^a is a top plan view of the needle-thread controlling device shown in Fig. 1. Fig. 2 is an end elevation of the 15 machine. Fig. 3 is a rear elevation of the machine-head and parts contiguous thereto. Fig. 4 is a sectional view taken on the line 3—3, Fig. 3. Fig. 5 is a perspective view of the rocking frame and bellerank-lever which 20 impart compound movements to the loopers. Fig. 6 is a perspective view of the crank-carrying end of the auxiliary or looper actuating shaft. Fig. 7 is a fragmentary view of the machine head, showing the mechanism for locking the main-shaft. Fig. 8 is an elevation of the lower part of the machine head looking toward the right in Fig. 3. Fig. 9 is a partially disassembled perspective view of the looper-carrier and 30 looper-levers. Fig. 10 is a top plan view of the presser-foot. Fig. 11 is a bottom plan view of the same. Figs. 12 to 15 inclusive are plan views illustrating the four successive positions assumed by the looper-thread 35 tubes relative to the needles during a complete cycle of movement. Fig. 16 illustrates the four needles coöperating with three rearwardly disposed looper-tubes to form the so-called "figure 8" stitches. Fig. 17 40 illustrates the four needles coöperating with three forwardly disposed looper-tubes to form an ornamental seam having a characteristic appearance differing from that shown in Fig. 16. Fig. 18 illustrates the 45 four needles coöperating with one rearwardly disposed looper tube and two forwardly disposed looper-tubes to form a seam differing from those shown in Figs. 15, 16 and 17. Fig. 19 is a plan view on an enlarged scale of the seam illustrated in Figs. 50 12 to 15 inclusive. Figs. 20 to 30 inclusive illustrate a few characteristic types of ornamental seams produced by the machine.

The improvements are shown embodied in 55 a machine having a bed-plate A, standard B, hollow overhanging arm C and head D. Extending within and lengthwise of the arm C is the main-shaft 1 provided at one end with the hand-wheel 2 and grooved belt- 60 pulley 3, and at its opposite end carrying the crank-disk 4, the latter being operatively connected with the needle-bar 5 by means of the crank-pin 6 and pitman 7. In the present instance the needle-bar has fixed thereon 65 at its lower end the clamp 8 for the four

needles n' , n^2 , n^3 , n^4 , which are arranged in a plane transverse to the line of seam-formation and which are adapted to coöperate with any desired form of supplemental loop-taking means such as single 70 chain loopers, one of which is shown at n , Fig. 2.

Mounted in the head D, parallel with the needle-bar, is a presser-bar 9 of usual construction, to the lower end of which is 75 clamped the shank 10 of a presser-foot p , Figs. 2, 10 and 11. The lower enlarged end of the shank 10 is formed with spaced rearwardly extending ears 11, which support the pivot-pin 12 on which are fulcrumed for independent movement the three supporting levers 13, 13 and 14, at the forward free ends of which are pivotally mounted the main sole-positions or feet 15, 15 and the chaining foot 16, respectively. Springs 17 80 are provided to yieldingly press the levers 13, 13 and 14 toward the bed-plate, and screws 18 threaded into said levers and loosely fitted in recesses in the enlarged lower end of the shank 10 are provided to limit 85 the downward movement of said levers relative to the shank 10. Acting in conjunction with the springs 17 to force the levers 13, 13 downwardly, are the springs 19, the pressure of which may be regulated by the 90 thumb-nuts 20 on the threaded rods 21 pivotally connected at 22 to the presser-foot shank 10. The presser-bar 9 is pressed downwardly by means of the usual spring 23, Fig. 7, and may be lifted by the hand-lever 24 or the treadle-controlled lever 25, each of which is arranged to act on the upwardly and outwardly bent bar 26 projecting laterally from the collar 27 fixed to the 95 presser-bar 9.

In the present instance the ornamental thread is presented to the needles by thread-carrying loopers mounted on the presser-bar for universal movement laterally of the needles. Fixed to the presser-bar 9, Fig. 4, 100 just below the collar 27, is the support for the loopers in the form of a block 28 carrying the rearwardly projecting pin 29 surrounded by the tubular boss 30 formed integral with the carrier plate 31, which is disposed directly at the left side of the needle-bar 5, Fig. 1. Referring now to Fig. 9, the carrier plate 31 is provided with two parallel pins 32, 33 which extend preferably in a direction at right angles to the axis of the 105 tubular boss 30 and form fulcrum supports for the downwardly extending looper-levers 34, 35, respectively. Split collars 36 are provided to hold the looper-levers in position on their fulcrum pins. The looper-lever 34 includes an extension 37 which crosses the line of seam-formation in rear of the needles and is slotted at 38 to form a seat for the shank of the looper 39 whose lower free end carries two thread tubes 40, 110

40 which project forwardly toward the plane of the needle. The looper-lever 35 is provided with a recess 41, Fig. 2, forming a seat for the looper 42 which extends down-
5 wardly in front of the needles and carries at its free end a thread-tube 43 directed toward the plane of the needles. The rear-
wardly disposed thread-tubes 40, 40 are spaced apart a distance equal to twice the
10 distance between adjacent needles and the forwardly disposed thread-tube 43 is so positioned that its free end is directed toward a position midway between the thread-tubes 40, 40 as shown in Figs. 12 to 15 inclusive.
15 Or, in other words, the thread-tubes are arranged alternately on opposite sides of the row of needles in spaced relation trans-
versely of the line of seam formation.

It will be seen that movement of the car-
20 rier-plate 31 about the supporting pin 29 will cause the looper-levers to move in uni-
son laterally of the line of seam-formation. To cause the looper-levers to move simulta-
25 neously toward or away from the plane of the needles an intermediate lever 44 is pro-
vided. This lever is pivoted between its ends to the carrier plate 31 by a screw-pin 45 and carries at its opposite ends the oppo-
30 sitely directed pins 46, 46 which freely enter apertures formed in the headed pins 47, 47 which in turn are journaled in the apertured bosses 48, 48 formed integral with the looper-levers 34 and 35 respectively.

The thread-looping implements or loopers 39 and 42 receive their operative movements from a bellerank-lever 49 which partakes of a compound motion resulting from two dis-
35 tinct motions imparted to the bellerank-lever in transverse directions. To this end the looper-lever 34 is provided with a short de-
pending pin 50 loosely received within the aperture 51 of the adjustable end-section 49' of the bellerank-lever 49 which is fulcrumed at 52 to a rocking frame 53 journaled on a
40 sleeve 54, Figs. 4 and 8, which in turn is journaled on a pin 55 screwed into the bracket 56 fixed to the head D. The looper-
lever 35 is also provided with a short de-
pending pin 50' which is loosely received
45 with the elongated aperture 51' of the end-
section 49' and assists in keeping the looper 42 in proper position relative to the looper 39 laterally of the line of seam-formation.

The means for imparting the compound
50 operative movements to the bellerank-lever 49 will now be described. Secured to the main-shaft 1 is the worm 57 meshing with the gear 58 mounted on the auxiliary shaft 59 which is journaled transversely of the
55 main-shaft in a housing 60 mounted on top of the bracket-arm C. The auxiliary shaft 59 is provided with an outboard projection formed with the ball crank-pins 61 and 62 whose centers are arranged in different
60 radial planes intersecting the axis of the

auxiliary shaft 59; the angle defined by said planes being, in the present instance, some-
what less than 90°.

Surrounding the ball crank-pin 61 is the strapped end of the pitman 63 whose oppo-
70 site apertured end embraces a pin 63' adjust-
ably mounted on the slotted crank-arm 64 which is fixed to one end of the tubular
shaft 54, to the opposite end of which is clamped the split end of an upstanding
75 crank-arm 65 carrying a ball-stud 66 which is connected by the link 67 to the ball-stud
68 mounted on the bent end-portion 49' of the bellerank-lever 49. The crank-arm 65 and link 67 constitute a toggle-device which
80 imparts two complete oscillations to the bellerank-lever 49 for each complete oscil-
lation of the crank-arm 65, or in other words,
for each rotation of the auxiliary shaft 59.
85 Since the main-shaft 1 rotates twice for each
rotation of the auxiliary shaft it follows
that the loopers 39 and 42 are moved toward
and away from the needles once during one
up-and-down movement of the needles.

Upon the ball crank-pin 62 is fitted the
connection block 69 formed with a sleeve 70
which slidingly receives the reduced upper
end portion of the lever-arm 71 whose lower
end is rigidly secured within the apertured
boss 72 formed integral with the rocking
frame 53. Through this line of connections
the bellerank-lever 49 is oscillated laterally
of the line of seam-formation at half the
frequency of oscillation of said bellerank-
lever about its fulcrum 52.

A simplified mechanism is provided for
positively and accurately controlling the
amount of ornamental thread supplied to
the loopers 39 and 42. Fixed to the needle-
bar and projecting through a slot s in the
100 face plate f is a block 73, Fig. 1 to the pro-
jecting end of which is screwed the enlarged
shank of an upwardly extending thread-
controlling implement 74 upon which is
mounted a roller-stud 75 constituting a pro-
jection adapted to actuate the nipper-lever
76 which is fulcrumed on the pin 77 sup-
ported by spaced lugs 78 formed on a pro-
jection 79 fixed to the face plate f. Secured
105 to the nipper-lever 76 just above the ful-
crum-pin 77 is an upwardly extending nip-
per-spring 80 formed with three thread nip-
ping tongues 81 whose upper end portions
are adapted to nip the ornamental threads
against a fixed nipper-plate 82 provided
110 with three thread-guiding apertures 83 lo-
cated just above the free ends of the tongues
81 of the nipper spring 80. A small coil-
spring 84 is provided to move the tongues 81
away from the nipper-plate 82. The nipper-
lever 76 is formed with an inclined portion
85 which is so disposed relative to the roller-
stud 75 that during the first part of the down
stroke of the needle-bar, the roller-stud 75
strikes said inclined portion 85 and causes
115

the thread to be nipped just before the needles enter the work. The main-portion of the nipper-lever 76 is at this time substantially parallel to the needle-bar and the roller-stud 75 maintains the nipper-tongues 81 in active position until the needles rise from the work.

The free end of the thread controlling implement 74 is curved rearwardly and down-wardly and carries a horizontally disposed thread engaging bar 86 which is reciprocated vertically between the nipper plate 82 and a plate 87 whose slotted shank 88 is adjustably secured to the tension-supporting bracket 89 fixed to the face-plate *f*. The adjustable plate 87 is provided with thread guiding apertures 90 disposed directly behind the apertures 83. During the last part of the down stroke of the needle-bar the thread is nipped and the pull-off implement strikes the ornamental thread extending between the thread-apertures 90 and 83 and pulls a predetermined length of thread through the tensions *t* which are carried by the bar 89. By shifting the plate 87 vertically the pull-off action of the implement 74 may be varied to cause the ornamental threads to be incorporated, either loosely or tightly, into the seam structure.

30 The machine is equipped with a multiple needle-thread controlling device actuated by the cam 91 on the main-shaft 1. The cam or eccentric 91 acts to lift the roller 92 pivoted to the lower end of a vertical rod 93 slidably mounted in the apertured post 94 secured to the frame. To the upper end of the rod 93 is secured centrally of its length the horizontal thread engaging bar 95 whose extremities 96 are turned upwardly. A spring 40 97 is provided to maintain the roller 92 in contact with the eccentric member 91. The sheet-metal bracket 98 mounted on the frame is formed with a pair of oppositely extending bent wings 99 embracing the path 45 of movement of the thread engaging bar 95 and provided with thread guiding apertures 100 disposed in a plane parallel to the bar 95 so that the threads are all treated equally by the device. The bar 95 serves in its upward movement to take up the slack in front of the descending needles before the needle points enter the work, and in its downward movement to give up slack required by the rising needles.

55 The manner in which the loopers 39 and 42 cooperate with the needles to form an ornamental seam may be understood from an inspection of Figs. 12-15 inclusive. Fig. 12 illustrates the cooperative relation 60 of the thread-tubes 40, 40, 43 and the needles *n'*, *n²*, *n³*, *n⁴* at the period in the stitch-forming cycle at which the needle points are just entering the fabric, the needles *n'*, *n²* and *n³* having passed down close beside the thread-tubes 40, 43, 40, respectively.

Fig. 13 illustrates the position of the parts as the rising needles are just leaving the fabric, the thread-tubes having been released from the plane of the needles and moved slightly to the right. The work is now fed to a stitch-length during which time the thread-tubes are moved to the right and projected toward the plane of the needles, passing under the then raised needle points to the position shown in Fig. 14 wherein the needle points are again entering the fabric. In this position the thread-tubes 40, 40 are laying their respective threads, previously caught by the needles *n'*, *n²*, about the needles *n²*, *n⁴*, while the thread-tube 43 lays its thread, about the needle *n³*. Fig. 15 shows the position of the parts as the needles are subsequently leaving the fabric. During the next feeding stroke the thread-tubes are moved toward the position shown in Fig. 12 for a repetition of the cycle of operation.

It will be apparent from the foregoing description that the needles and loopers are in very close proximity to each other and the thread-tubes passing in their immediate movement under the points of the needles. In removing work from the machine it is necessary to lift the presser-foot which, however, should not be done when the thread-tubes are directly under the needle points for the reason that the thread-tubes will strike the needles and damage the machine. Furthermore, the machine should not be turned over with the presser-foot in elevated position as the loopers are not positioned in proper cooperative relation with the needles and may strike the latter. To guard against possible damage resulting from careless operation of the machine, I have provided a slot 101 in the upright post 94, Fig. 7, which, when the needle-bar is in its highest position, is in alignment with an upwardly extending pin or projection 102 carried by the collar 27. By virtue of this construction the presser-bar cannot be lifted until the machine is stopped with the needle-bar in its highest position and while the presser-bar is lifted the pin 102 serves to lock the main-shaft against rotation.

By removing the looper 42 and substituting a triple tube looper 39', a seam comprising three connected rows of closed loop or "figure 8" stitches are formed, as shown in Fig. 16. Similarly, by removing the looper 39 and substituting a triple tube looper 42', a seam comprising three connected rows of open loop ornamental stitches, such as shown in Fig. 17, are formed. Still another combination may be effected by substituting a double tube looper 42" for the looper 42 and a single tube looper 39" for looper 39 thus forming the seam illustrated in Fig. 18.

Various effects may be produced by omitting one or more threads from certain of the

- the needles and loopers in any of the above described combinations. For example, the seam shown in Fig. 20 may be produced by omitting the ornamental thread from the 5 central looper-tube on the looper 42', Fig. 17. The seam shown in Fig. 21 may be produced by omitting needle-thread from the needles n^1 , n^2 , n^4 and ornamental thread from the looper-tube shown at the right in 10 Fig. 16. When ornamental threads having the same twist are used in producing this seam the effect will be as shown in Fig. 21, wherein the outwardly disposed free loops of the left-hand thread are open. When 15 oppositely twisted threads are employed the seam will have a symmetrical appearance. From the foregoing description it is believed that the method of producing the various seams illustrated in Figs. 22, 23, 24, 20 29 and 30 will be obvious and that further description thereof is unnecessary.

Fig. 21 illustrates the use of the seam disclosed in Fig. 17, as an ornamental edging. In the seam shown in Fig. 26, the ribbon or 25 tape s may be secured to the base fabric b by two rows of "figure 8" stiches, in one operation, or a fancy band may be produced by stitching along both edges of the ribbon s omitting the fabric b . Similarly in Fig. 30 28, two ribbons or tapes s' may be secured to a base fabric b' , or the fabric b' may be omitted. Various other possible combinations will readily suggest themselves to those skilled in the art and need not be specifically 35 referred to herein.

While I have shown and described what I consider to be the preferred embodiment of the invention, it is to be understood that the improvements are susceptible of considerable modification both in the form and arrangement of the various parts within the scope of the invention.

Having thus set forth the nature of the invention, what I claim herein is:

45 1. In an ornamental stitch sewing machine, in combination, stitch-forming mechanism including a pair of reciprocating needles and complementary loop-taking means, and ornamental thread-forming mechanism including a looper, a looper-support, said looper having a universal connection with its support, whereby it may move in different directions transversely of the needles to present the thread thereto in alternation, and loop-forming means including a pair of cranks for imparting to the looper its operative movements.

2. In an ornamental stitch sewing machine, in combination, stitch-forming mechanism including a pair of reciprocating needles, an endwise movable presser-bar, a looper for the ornamental thread, a looper lever carrying said looper, a support fixed to the presser-bar, a universal connection between said looper-lever and said support,

whereby said looper-lever may move in different directions transversely of the needles to present the thread thereto in alternation, a fixed support, an actuating lever freely connected with said looper-lever and having a universal connection with said fixed support, and means for simultaneously moving said actuating lever in directions at an angle to each other.

3. In an ornamental stitch sewing machine, the combination with stitch-forming mechanism including a reciprocating needle and complementary loop-taking means, of a pair of ornamental thread-loopers having their respective paths of movement in front and in rear of the needle path, and actuating means for causing said loopers to present their respective threads to said needle.

4. In an ornamental stitch sewing machine, in combination, stitch-forming mechanism including a reciprocating needle and complementary loop-taking means, a pair of loopers each mounted for universal movement transversely of said needle and adapted to guide an ornamental thread thereto, so said loopers being arranged in front and in rear of the needle, respectively, and means for imparting operative movements to said loopers whereby they are caused to present their respective threads to said needle in alternation.

5. In an ornamental stitch sewing machine, the combination with stitch-forming mechanism including a plurality of needles disposed in a plane crossing the line of 100 seam-formation, and complementary loop-taking means, of a pair of ornamental thread-loopers having their respective paths of movement mainly at opposite sides of the plane of said needles, and actuating 105 means for causing said loopers to present ornamental thread to said needles.

6. In an ornamental stitch sewing machine, in combination, stitch-forming mechanism including a plurality of reciprocating needles and complementary loop-taking means, comprising a pair of loopers each adapted to guide an ornamental thread to one of the needles, said loopers being disposed one in front and one in rear of the needles and having a universal connection with said support, whereby said loopers may move in different directions transversely of said needles, and means for imparting operative movements to said loopers.

7. In an ornamental stitch sewing machine, in combination, a reciprocating needle-supporting presser-bar, complementary loop-taking means, a looper support, a looper lever movably mounted on said support and disposed mainly at the side of the needle-bar and the line of seam-formation, a pair of loopers pivotally mounted on said carrier, and including loopers disposed one in front and one in

rear of said needle and adapted to co-operate therewith.

8. In an ornamental stitch sewing machine, in combination, a plurality of at least three reciprocating needles disposed in a row extending transversely of the line of seam-formation, complementary loop-taking means, a pair of thread-looping implements including extensions disposed, respectively, in front and in rear of the needles, said extensions including apertured thread-guiding portions directed toward the row of needles and arranged alternately on opposite sides of said row of needles in spaced relation transversely of the line of seam-formation.

9. In an ornamental stitch sewing machine, in combination, stitch-forming mechanism including a plurality of needles arranged substantially in a plane transversely of the line of seam-formation, a support, a carrier pivotally mounted on said support, a pair of looper-levers pivotally mounted on said carrier, a looper secured to each of said looper-levers, said loopers being arranged one in front and one in rear of the plane of the needles, and each including a thread-tube directed toward said needles, and means for simultaneously rocking said carrier and said looper-levers about their pivots.

10. In an ornamental stitch sewing machine, in combination, a plurality of reciprocating needles arranged in a plane transversely of the line of seam-formation, complementary loop-taking means, a pair of loopers for the ornamental threads, each of said loopers being mounted for universal movement transversely of said needles and being disposed one in front and one in rear of the needles, means for imparting simultaneous movements to said loopers transversely of the line of seam-formation and means for simultaneously moving said loopers toward and away from the plane of the needles.

11. In an ornamental stitch sewing machine, in combination, stitch-forming mechanism including a plurality of reciprocating needles arranged in a plane transversely of the line of seam-formation, a support, a carrier pivotally mounted on said support, a pair of looper-levers pivotally mounted on said carrier, a looper secured to each of said looper-levers, said loopers being arranged, respectively, in front and in rear of the plane of the needles, and each including a thread-tube directed toward the plane of the needles, and means for simultaneously rocking said carrier and said looper-levers about their pivots, said means including connections with said looper-levers whereby they are caused to simultaneously approach and recede from the plane of the needles.

12. In an ornamental stitch sewing machine, in combination, stitch-forming mechanism comprising a reciprocating needle and complementary loop-taking means, a movable carrier, a pair of looper-levers pivoted to said carrier, loopers mounted, respectively, on said looper-levers, said loopers being disposed on opposite sides of the needle-path, means for moving said carrier, and means for swinging said looper-levers about their respective axes, said last mentioned means including a lever mounted on said carrier and connected at its opposite ends to said looper-levers.

13. In an ornamental stitch sewing machine, in combination, stitch-forming mechanism including a needle and complementary loop-taking means, a thread-looping implement mounted for movement in different directions transversely of the needle to present thread thereto, actuating means for said thread-looping implement comprising a movable support, a lever pivotally mounted on said support for movement in a direction transverse to the direction of movement of said support, means for moving said support, and a toggle-device for rocking said lever about its pivot.

14. In an ornamental stitch sewing machine, in combination, stitch-forming mechanism, a main-shaft, a pair of cranks connected to said shaft, a rocking frame connected to one of said cranks, a lever pivotally mounted on said frame, connections between said lever and the other of said cranks including a toggle-device, whereby the frequency of oscillation of the lever about its pivot is double that of the rocking frame, and thread-looping means connected to said lever and co-operating with said stitch-forming mechanism.

15. In an ornamental stitch sewing machine, in combination, stitch-forming mechanism including a main-shaft and a needle reciprocated thereby, an auxiliary shaft connected to be driven at half the speed of the main-shaft, a pair of cranks on said auxiliary shaft, a rocking frame connected to one of said cranks, a lever pivotally mounted on said frame, connections between said lever and the other of said cranks including a toggle-device, whereby the frequency of oscillation of the lever upon its pivot is double that of the rocking frame, and thread-handling means connected to said lever and co-operating with said needle.

16. In an ornamental stitch sewing machine, in combination, stitch-forming mechanism comprising a reciprocating needle and complementary loop-taking means, a looper for presenting the ornamental thread to the needles, and looper-actuating mechanism comprising a pivotally mounted rocking frame, a lever pivoted to said frame on an

- axis transverse to the axis of movement of said frame, a shaft mounted coaxially with said axis of movement and a toggle connection between said shaft and said lever.
5. 17. In an ornamental stitch sewing machine, in combination, stitch-forming mechanism including a reciprocating needle and complementary loop-taking means, an endwise movable presser-bar carrying a presser-
10 foot, a thread-looping element mounted on said presser-bar for universal movement transversely of said needle, an actuating device for said thread-looping element including a fixed support and an actuating element mounted on said support for universal movement transversely of said needle, a pin carried by one of said elements and extending mainly in the direction of movement of the presser-bar, the other of said
20 elements being provided with a recess entered by said pin.
18. An ornamental stitch sewing machine comprising, in combination, a main-shaft, a reciprocating needle and complementary loop-taking means driven by said main-shaft, an auxiliary shaft connected to be driven at one-half the speed of the main-shaft, a pair of cranks on said auxiliary shaft, a looper for the ornamental thread mounted for universal movement transversely of said needle and operative connections between said cranks and said looper.
19. An ornamental stitch sewing machine comprising, in combination, a main-shaft, a reciprocating needle and complementary loop-taking means driven by said main-shaft, an auxiliary shaft connected to be driven at one-half the speed of the main-shaft, a pair of cranks on said auxiliary shaft, a looper for the ornamental thread mounted for universal movement transversely of said needle and link-and-lever connections between said cranks and said looper.
20. In an ornamental stitch sewing machine, in combination, a reciprocating needle-bar carrying a needle, complementary loop-taking means, a looper mounted adjacent the needle-bar for universal movement transversely of said needle, and thread measuring means for the ornamental thread including a thread-nipper, and an implement carried by said needle-bar having a portion adapted to actuate said thread-nipper and another portion adapted to pull thread from the supply.
21. In an ornamental stitch sewing machine, in combination, a reciprocating needle-bar carrying a needle, complementary loop-taking means, a looper mounted adjacent the needle-bar for universal movement transversely of said needle, and thread measuring means for the ornamental thread including a thread-nipping lever having straight and inclined portions, and an imple-
65 ment carried by said needle-bar having a projection adapted to engage and actuate said lever and a portion adapted to pull thread from the supply.
22. In a sewing machine, in combination, a needle, complementary loop-taking means, a looper, a support therefor, means for lifting said support, and means serving to lock the machine when said support is lifted.
23. In a sewing machine, in combination, a main-shaft, a needle-bar reciprocated thereby and carrying the needle, complementary loop-taking means, an endwise movable presser-bar, a looper movably supported by said presser-bar for co-operation with said needle, lifting means for said presser-bar, and means connected to said presser-bar and said main-shaft coacting to lock the latter against rotation when said presser-bar is lifted.
24. In a sewing machine, in combination, a reciprocating needle, complementary loop-taking means, a looper, a support for said looper, lifting means for said support, and means serving to render said lifting means ineffective except when the looper is in a predetermined position.
25. In a sewing machine, in combination, a main-shaft, a needle-bar reciprocated thereby and carrying the needle, complementary loop-taking means, an endwise movable presser-bar, a looper movably supported by said presser-bar for co-operation with said needle, lifting means for said presser-bar, and means connected to said presser-bar and said main-shaft coacting to prevent upward movement of the presser-bar except when the looper is in a predetermined position.
26. In a sewing machine, in combination, a main-shaft, a needle-bar reciprocated thereby and carrying the needle, complementary loop-taking means, an endwise movable presser-bar, a looper movably supported by said presser-bar for co-operation with said needle, lifting means for said presser-bar, and means connected to said presser-bar and said main-shaft coacting to prevent upward movement of the presser-bar except when the looper is in a predetermined position, and to lock the main-shaft against rotation when said presser-bar is lifted.
27. In a sewing machine, in combination, a main-shaft, a crank-disk carried thereby, a reciprocating needle connected to said crank-disk, complementary loop-taking means, an endwise movable presser-bar, a looper movably supported by said presser-bar for co-operation with said needle, lifting means for said presser-bar, and means connected to said presser-bar and said crank-disk coacting to lock the latter against rotation when said presser-bar is lifted.

38. In a sewing machine, in combination, a main-shaft, a crank-disk carried thereby and having a recess, a reciprocating needle connected to said crank disk, complementary loop-taking means, an endwise, movable presser-bar, a looper movably supported by said presser-bar for cooperation with said needle, lifting means for said presser-bar, and a projection carried by said presser-bar and adapted to enter said recess when the presser-bar is lifted.

39. In an ornamental stitch sewing machine, the combination with a plurality of reciprocating needles arranged in a row transverse to the line of seam-formation and thread carrying loopers adapted to present ornamental threads to said needles, of a presser-foot comprising a shank; a pair of main levers each carrying a pivotally mounted sole-piece, the forwardly disposed portions of said sole-pieces being arranged closely adjacent one another, said sole-pieces being cut away in rear of said forwardly disposed portions to form an opening for the needles, and a third lever disposed be-

tween said main-levers and carrying a pivotally mounted chaining foot, serving to close the rearward side of said opening.

40. In an ornamental stitch sewing machine, in combination, a reciprocating needle, a complementary loop-taker, feeding mechanism, a plurality of loopers for ornamental threads, and means for imparting components of motion to said loopers simultaneously in the same direction transversely of the line of feed and simultaneously in opposite directions parallel with the line of feed.

41. In a sewing machine, in combination, stitch-forming mechanism comprising a plurality of reciprocating needles arranged in a plane crossing the line of feed and complementary loop-taking means for forming a plurality of at least three rows of stitches, and thread-looping devices for looping a separate cross thread back and forth between each two adjacent rows, respectively.

In testimony whereof I have signed my name to this specification.

ALBERT H. DE VOE.
